UNITED STATES PATENT OFFICE.

ELIAS JAFFE, OF NEW YORK, N. Y.

BUTTON-ATTACHING MEANS.

Application filed July 5, 1927. Serial No. 203,367.

The present invention relates to button structure of the type in which a sheet metal part has prongs struck therefrom for insertion through a fabric to be clinched to secure the button in position. An object of the invention is to provide a button structure of the kind described in which are included means for strengthening the portion of the sheet metal from which the prongs have been cut. Another object of the invention is to provide a pronged sheet metal button structure in which a section of the sheet between the prongs cooperates with the prongs in holding a fabric attached from disengaging movement. Other objects and advantages will appear from the drawings and from the following particular description of forms of button structures used to illustrate the invention, and the invention also consists in the parts and combinations of parts particularly set forth in the claims.

In the drawings, in which like reference characters refer to like parts throughout, there is shown for purposes of illustration various embodiments of the invention in which Figure 1 is a plan view of a fabric piece and a button attached thereto, Figure 2 is a reverse plan view of the fabric showing attaching means, Figure 3 is a vertical sectional elevation view of a button attached to a fabric, Figure 4 is a plan view of a fabric piece with the button part of a button attached thereto, Figure 5 is a reverse plan view with the fabric in part cut away, Figure 6 is a view similar to that of Figure 4 showing an alternate form of attachment, and Figure 7 is a view similar to that of Figure 2 but without the clinching ring shown in Figure 2.

In Figures 1 to 4 of the drawings a bottom part 1 of a button is of sheet metal and is cup shaped with V-shaped cuts 2, 2 made in the bottom thereof to form V-shaped prongs 3, 3 positioned diametrically opposite each other, said cuts 2, 2 defining triangular openings 4, 4 in the bottom of part 1 when said prongs 3, 3 are bent therefrom. Said openings 4, 4 are adjacent each other with respective sides of cuts 2, 2 parallel to each other and with a strip 5 of the metal of part 1 left between them. In the preferred form of assembly to a fabric a ring 6 is provided through the central opening of which the prongs 3, 3 extend after being inserted through a piece of fabric 7. The prongs 3, 3 are then clinched or bent over the ring

6 and their ends pushed into said fabric 7 to bind the fabric securely to the button structure, particularly against the edges of said triangular shaped openings 4, 4 at the edges 60 of said strip 5 and against the other edges of said openings. By this arrangement there is prevented any movement of the fabric such as will allow the release of the fabric from said prongs 3, 3. The top cap 65 8 fits onto said bottom part 1 and binds in place the fabric covering 9 which extends over the top and has its edges folded around the annular edge of cap 8.

In Figure 5 is an alternative embodiment 70 in which a bottom part 1' has formed therein two prongs 3', 3' whose bases are oppositely positioned with respect to each other, said prongs 3', 3' being inserted through a fabric 10 and through the central opening 75 of a metal ring 11 over which they are bent and clinched into the fabric on the outside of the ring. In this form the ring 11 extends over the triangular openings 12, 12 formed when said prongs 3', 3' are cut and binds 80 the fabric tightly against the edges of said openings 12, 12.

In Figure 6 is illustrated the same form of structure as in Figures 2, 3 and 4 except that no ring is used and the prongs 3, 3 85 are bent inwardly after being inserted through the fabric 7 and again inserted through the fabric and clinched thereon. In Figure 7 is again shown the same form as in Figures 2, 3, 4 and 6 and without the 90 use of the clinching ring. In this form the prongs 3, 3 are bent outwardly as in Figures 2 and 3 but clinched directly against the fabric 7 without the use of the interposing ring.

Although I have set forth and described various embodiments of my invention, it is obvious that various changes, substitutions and omissions may be made in the parts and combinations without departing from the 100 spirit of the invention.

Having thus described my present invention, I claim:

1. A button structure comprising a top section, and a bottom section of sheet metal 105 provided with laterally spaced apart prongs cut from the metal of said bottom section, with a strip of said bottom section between the incisions of said prongs, the points of said prongs being oppositely directed in the 110 surface of said bottom section.

2. In a button structure a fastening por-

tion comprising a sheet metal piece having V-shaped cuts therein spaced from each other laterally and having a strip of said sheet metal piece between the incisions of 5 said prongs with the points of the V's pointing in opposite directions.

3. In a button structure a fastening portion comprising a sheet metal piece having V-shaped cuts therein spaced apart laterally with the points of the V's directed oppositely, and a strengthening bar between the sides of adjacent V-cuts unitary with 10 said sheet.

4. In a button structure, a fastening portion comprising a sheet metal piece provided with laterally adjacent V-shaped cuts to form prongs oppositely directed in the 15 surface of said piece and a strengthening bar unitary with said piece and extending 20 along and between adjacent sides of said V-shaped cuts.

5. In a button structure, a fastening portion comprising a ring member, and a section of sheet metal provided with prongs 25 cut from within the confines thereof and adapted to be bent away from the surface of said sheet metal section and over the edge of said ring member.

6. In a button structure, a fastening portion comprising a ring member, and a sec- 30

tion of sheet metal provided with prongs cut from within the confines thereof and adapted to be bent away from the surface of said metal section and to extend through the opening of said ring and to be bent over 35 the side of said ring.

7. A button structure comprising a ring member, and a section of sheet metal provided with V-shaped cuts therein spaced from each other laterally with the points of 40 the V's extending in opposite directions and with a strengthening and binding strip left between the sides of adjacent V's, said V-cuts defining prongs adapted to be bent away from the surface of said sheet and to 45 be inserted through a fabric and bent over the edges of said ring when placed on said fabric on an opposite face to said sheet metal section to bind said fabric securely between said sheet section and said ring, and said strengthening and binding strip adapted by its position between the V-cuts to hold the fabric adjacent thereto against 50 substantial flexure through the openings left at said prongs.

In testimony that I claim the invention set forth above I have hereunto set my hand this 29th day of June, 1927.

ELIAS JAFFE.
